US0D1054403S

(12) **United States Design Patent** (10) **Patent No.:** **US D1,054,403 S**
(45) **Date of Patent:** **** Dec. 17, 2024**

(54) **MICROPHONE**

(71) Applicant: **Focusrite Audio Engineering Limited**,
High Wycombe (GB)

(72) Inventors: **Orla Haigh**, Cheltenham (GB); **Ryan Gray**, Hazlemere (GB); **Joshua Wilkinson**, Aylesbury (GB)

(73) Assignee: **Focusrite Audio Engineering Limited**,
High Wycombe (GB)

(**) Term: **15 Years**

(21) Appl. No.: **29/865,921**

(22) Filed: **Aug. 20, 2022**

(30) **Foreign Application Priority Data**

(57) **CLAIM**

The ornamental design for a microphone as shown and described.

DESCRIPTION

FIG. 1 is a left side perspective view of the microphone;
FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines depict portions of the microphone that
form no part of the claimed design.

1 Claim, 5 Drawing Sheets
